US00D895812S

(12) **United States Design Patent** (10) **Patent No.:** **US D895,812 S**
(45) **Date of Patent:** **** Sep. 8, 2020**

(54) **SOFT TISSUE REPAIR GRAFT**

- (71) Applicants: **Musculoskeletal Transplant Foundation**, Edison, NJ (US); **The Methodist Hospital**, Houston, TX (US)
- (72) Inventors: **Aldona Jedrysiak Spiegel**, Houston, TX (US); **Kai-Roy Wang**, Jersey City, NJ (US)

- (73) Assignee: **Musculoskeletal Transplant Foundation**, Edison, NJ (US)

- (**) Term: **15 Years**

- (21) Appl. No.: **29/662,750**

- (22) Filed: **Sep. 7, 2018**

- (51) LOC (12) Cl. **24-01**

(57) **CLAIM**

An ornamental design for a soft tissue repair graft, as shown and described.

DESCRIPTION

FIG. 1 is a top plan view of a soft tissue repair graft showing our new design;

FIG. 2 is a bottom plan view thereof;

FIG. 3 is a left side elevational view thereof;

FIG. 4 is right side elevational view thereof;

FIG. 5 is a front elevational view thereof; and,

FIG. 6 is a rear elevational view thereof.

The broken lines in the figures depict claimed portions of a soft tissue repair graft.
